UNITED STATES PATENT OFFICE.

JOHN L. O'DONNELL, OF ST. LOUIS, MISSOURI.

COVER FOR ATHLETIC GROUNDS.

974,091.

Specification of Letters Patent. Patented Oct. 25, 1910.

Application filed October 13, 1909. Serial No. 522,432.

To all whom it may concern:

Be it known that I, JOHN L. O'DONNELL, a citizen of the United States, and resident of St. Louis, Missouri, have invented certain new and useful Improvements in Covers for Athletic Grounds, of which the following is a specification containing a full, clear, and exact description, reference being had to the accompanying drawings, forming a part hereof.

My invention relates to improvements in the construction of athletic grounds and a removable cover therefor to protect the ground from rain, the primary object of my invention being to construct drains either around or through an athletic grounds to provide a cover of waterproof material for the grounds and to locate in said drains means for moving said cover either over or off of the grounds and to provide means in some of the drains to secure the margins of the cover opposed to the margins acted upon by the means for moving the cover.

A further object of my invention is to construct a movable cover for the drains which movable cover is provided with an upper face of yielding material.

For the above purposes my invention consists in certain novel features of construction and arrangement of parts as will be hereinafter more fully set forth, pointed out in the claims and illustrated in the accompanying drawings, in which:

Figure 1 is a diagrammatical view illustrating the arrangement of my improved drains and movable covers therefor as applied to a base ball diamond; Fig. 2 is an enlarged, longitudinal, sectional elevation through one of the end drains showing the relative positions of the intersecting drains and the arrangement of the cover for the diamond as in use; Fig. 3 is a plan of the means whereby the cover is either drawn over the grounds to cover them or drawn over the grounds to uncover them; Fig. 4 is a transverse, sectional elevation through one of the side drains showing the winding shaft for supporting and holding the cover, when not in use, and the means for supporting the winding shaft and cover intermediate their ends, the cover being shown as partially wound on the winding shaft; Fig. 5 is a transverse, sectional elevation through the central drain paralleling the side drains showing the arrangement of the winding drums and ropes for drawing the cover over

the grounds to cover them; Fig. 6 is a transverse, sectional elevation through one of the side drains, showing the cover completely wound upon the winding shaft and the movable padded cover for the drain in position closing the drain; and, Fig. 7 is a transverse, sectional elevation through the central drain paralleling the end drain and shows the means whereby the margins of the waterproof cover, opposed to the ends operated upon by the winding means, are secured within the drain.

The drawings represent my improved drains and cover as applied to a base ball diamond, but it is obvious that with slight changes and modifications the same may be applied to any outdoor athletic grounds.

In the drawings, the numeral 1 designates the side drains, 2 the central drain paralleling the side drains.

3 designates the end drains and 4 the central drain paralleling the end drains.

As shown in Fig. 2 the surface of the diamond inclines from left to right between the left hand side drain 1 and central drain 2 and between the central drain 2 and right hand side drain 1 and all of the drains are of substantially the same depth so that all of the water from the grounds may be conveyed through said drains and carried off from the lowermost drain by any suitable means, not shown, such as tiling or the like.

Each of the drains is preferably provided with reinforcing lining which is provided at their upper ends with opposing shoulders 5 and said lining is preferably made to terminate a slight distance below the ground line. Supported upon and secured to the lining is a pair of yielding strips 6 arranged to be flush with the ground, and, arranged to be supported upon the shoulders 5, is a removable cover 7 having a pad 8 secured thereto, which pad is of sufficient width to engage the inner margins of the strips 6 and is arranged to be flush with their upper faces.

Arranged in the drains 1 are the shafts 9 and 10 supported by the standards 11 upon the bottoms of the drains. Arranged to wind upon the shafts 9 are the two flexible waterproof covers 12 of a length sufficient to cover the portions 13 of the diamond, and, arranged upon the shafts 10 are the two flexible waterproof covers 14 of a length sufficient to cover the portions 15 of the diamond and each of the flexible covers 12 and 14

is of a width sufficient to reach from its winding shaft to the drain 2. Thus it is obvious that there are altogether four covers, one for each of the portions separated by the 5 cross drains as shown in Fig. 1.

The free margins of each of the flexible covers 12 and 14 are provided with a series of eyelets 16. Secured within the eyelets on the margins of the flexible covers, opposed 10 to the margins wound upon the shafts 9 and 10, are a number of ropes or cables 17.

Arranged within the drain 2 is a plurality of bearings 18 and supported within said 15 bearings are shafts 19, 20, 21 and 22 and carried by said shafts and secured against rotation thereon, are a series of drums 23, corresponding in number to the ropes 17 and to which the ends of the ropes 17, opposed 20 to their ends secured to the eyelets 16, are secured.

Each of the shafts 19, 20, 21 and 22 is provided with a gear wheel 24 and meshing therewith are the idlers 25 arranged upon the shafts 26, and meshing with the idlers 25 is a pair of gear wheels 27 and 28 arranged upon the shaft 29, and, carried by the shaft 29 is a sprocket wheel 30.

Arranged in the opening 31, which communicates with the drain 2, is a motor 32, 30 and embracing the shaft of the motor is a sprocket wheel 33 which is connected to the sprocket wheel 30 by means of the chain 34 and connecting with the sprocket wheel 33 is a crank arm 35.

Each of the idlers 25 is arranged to slide 35 upon their supporting shafts 26 and arranged adjacent each of the idlers is a lever 36 whereby the idlers 25 may be moved into or out of mesh with the gear wheels 24 and 40 27 and 28.

Arranged upon each of the winding shafts 9 and 10 is a gear wheel 37 and 38 respectively and meshing therewith are the idlers 39 supported upon the shaft 40 and arranged 45 for moving the idlers 39 longitudinally of the shaft 40 into or out of mesh with the gear wheels 37 and 38 are the levers 41.

Arranged to mesh with the idlers 39 is a pair of gear wheels 42 and 43 mounted upon 50 the shaft 44, and, carried by the shaft 44 is a sprocket wheel 45.

Located within the openings 46, communicating with the drains 1, are motors, such as 47, and embracing the shafts of the motors 55 are sprocket wheels such as 48, and embracing the wheels 48 and 45 are the sprocket chains 49 and connected with the sprocket wheels 48 are crank arms 50.

To support the shafts 9 and 10 and the 60 flexible covers 12 and 14, carried thereby, intermediate their ends, is a series of rollers 51 rotatably carried on the arms 52 which are pivoted within the pockets 53 formed in the side walls of the drain 1. Impinging 65 between the arms 52 and the bottom of the

drain are expansive coil springs 54 of sufficient strength to support the shaft and flexible cover wound thereon.

To provide means whereby the flexible covers are held to prevent movement in a 70 direction opposed to their winding and unwinding directions, a series of hooks 55 are arranged in the inside walls of the end drains 3 and on each wall of the drain 4 paralleling the end drains, and, are arranged to engage 75 in the eyelets 16. In this manner the flexible cover is secured against being blown from the diamond.

When it is desired to position the flexible waterproof covers over the diamond the 80 movable padded covers from each of the drains are removed and each of the ropes 17 is unwound from their respective drums 23 and manually drawn and secured to the eyelets 16 in the free margins of the flexible 85 waterproof covers and the motor 32 is then set in motion and through the medium of the sprocket chain 34 motion is imparted to the gear wheels 27 and 28. The idlers 25 are then brought to positions meshing with the 90 gear wheels 27 and 28 and also in mesh with the gear wheels 24 which are secured to the shafts 19, 20, 21 and 22 which imparts a rotary motion to each of the drums 23, thereby winding each of the ropes 17 and drawing 95 each of the flexible covers to positions covering the athletic ground. And, when in such positions two of their margins are secured beneath the ground line at one end upon the shafts 9 and 10 and their opposite 100 margins are secured beneath the ground line by placing the eyelets 16 over the hooks 55 in the end drains 3 and the central drain 4, thereby securely holding them against being blown from the ground surface.

When it is desired to remove the covers from the diamond, the motors 47 are set in motion and through the medium of the sprocket wheels 45 and 48 and sprocket chain 49, the gear wheels 42 and 43 are rotated and through the medium of the idlers 39 the gear wheels 37 and 38 are rotated thereby imparting motion to the shafts 9 and 10 to wind the flexible waterproof covers into positions uncovering the diamond; and when in such positions are wholly beneath the surface of the ground in the drains 1. The ropes 17 are then detached from the eyelets 16 and are wound upon the drums 23 wholly beneath the surface of the ground in 115 the central drain 2.

The padded covers 7 are then placed in positions closing the drains, and by reason of their padded tops 8, they present a surface of substantially the same quality as the 120 ground surface of the diamond.

If, for any reason, the motors 32 and 47 are temporarily inoperative, the winding shafts for the ropes and flexible covers may be operated manually through the medium 130

of the crank arms 35 and 50, and it is obvious by reason of the arrangement of the idlers for each of the winding shafts, the shafts may be operated separately or collectively.

To persons familiar with outdoor sports, it is known that a great number of scheduled games are postponed on account of "wet grounds," due to rains previous to the 10 times of the games.

By the employment of my improved, flexible, waterproof covering for the grounds, it is obvious that the grounds may be protected from such rains previous to the times of the 15 scheduled games, and, that if it is not raining at the appointed time for such games, the games may be played.

I claim:

1. In combination with an athletic grounds 20 having drains and an inclined surface between said drains, winding devices located in said drains, flexible water-proof covers carried by said winding devices and means for actuating the winding devices.

2. In combination with a flexible, water- 25 proof covering for athletic grounds, separate means for drawing the cover to positions covering or uncovering the grounds, means for securing the margins against being blown from the grounds, of drains for inclosing the means whereby the flexible cover is moved and for conveying the water 30 from said grounds.

3. In combination with an athletic grounds having drains, of winding devices located in 35 said drains and flexible waterproof covers carried by said winding devices.

4. In combination with an athletic grounds having drains, of winding devices located in 40 said drains, flexible waterproof covers ar- ranged on said winding devices, and means for actuating the winding devices whereby the covers may be drawn to positions either covering or uncovering the grounds and means for securing the margins of the cover 45 within said drains.

5. In combination with an athletic grounds having drains, provided with movable pad- 50 ded covers, of winding devices located in said drains, a plurality of flexible water- proof coverings arranged on said winding devices, means whereby the winding de- vices may be moved either separately or col- lectively for drawing the flexible covers to 55 positions either covering or uncovering the grounds and means for securing all of the margins of all of the flexible covers beneath the ground surface and in said drains.

In testimony whereof, I have signed my name to this specification, in presence of two 60 subscribing witnesses.

JOHN L. O'DONNELL.
